UNITED STATES PATENT OFFICE

FREDERICK A. CALKINS, OF WATERBURY, CONNECTICUT

WINDOW ADJUSTER

Application filed June 15, 1929. Serial No. 371,106.

This invention relates to improvements in window adjusters, and more especially storm windows or screens, such as are hingedly hung from one portion of a window casing and adapted to be swung out so that the sash may be adjustably supported at various positions with respect to the lower portion or sill of the frame.

The object of the invention is to provide a simple and inexpensive form of window adjuster, of the class specified which may be economically formed of sheet metal and adapted to be readily applied to both a window frame and hinged sash; further to provide an adjuster of the class specified which will be compact and applicable for attachment to the top of the window sill rather than the side or top portions of the window frame, and which, when so applied to the sill and sash, will lie close to the sill requiring a comparatively small amount of space and adapted to operate on a horizontal plane rather than a vertical plane.

The adjuster may be used singly or in pairs, as preferred and may be used for the adjustment of the lower portion of either a glass sash or a screen, hinged to swing out, and can be used either upon the bottom sill of a window frame or upon the under side of the top portion of the frame, if for any reason it may be necessary, or preferable to hinge the sash at the bottom instead of at the top.

The invention specifically resides in a window adjuster formed of relatively flat metal parts hingedly connected together, one end member of which is adapted for attachment to a window sill and the opposite end member constructed to be secured to the inner face of the sash. The connected ends of the two main foldable arms of the adjuster are hingedly connected to swing in a horizontal plane and upon a vertical pivotal pin, their outer ends being swivelly connected to said fixed members attached to said frame and sash, the said swivel connection allowing of both a horizontal swinging movement of said arms with respect to the fixed members, as well as a vertical movement of the outer members of the adjuster, better to permit the outer end

of the adjuster to be freely raised and lowered to accommodate itself to the elevated position of the lower part of the sash, when open.

With these and other objects in view, the invention resides and consists in the construction and novel combination and arrangement of parts hereinafter more fully described, illustrated in the accompanying drawings, and pointed out in the claim here-to appended, it being understood that various changes in the form, proportion, size, and minor details of construction within the scope of the claim may be resorted to without departure from the spirit, or sacrificing any of the advantages of the invention.

Similar characters of reference denote like or corresponding parts throughout the several figures of the accompanying drawings forming a part of this specification and upon which

Fig. 1 shows a sectional plan view through a window frame and sash, to which a pair of my improved window adjusters are shown secured and in a folded or closed position;

Fig. 2 shows a side elevation of my improved window adjuster, in an open position, and applied to a window frame and sash;

Fig. 3 is a plan view of the adjuster, applied to a window frame and sash in an open position;

Fig. 4 shows an enlarged vertical sectional view of the frictional hinge structure employed for connecting the adjoining ends of the two main adjuster arms together; and

Fig. 5 shows a similar vertical sectional view of the attaching means for securing the fixed end member of the adjuster to the window sill.

Referring in detail to the characters of reference marked upon the drawings, 10 represents a window frame, 11 a sash or screen represented as being hingedly connected at the top to the frame, so that its lower end portion may be swung to and from the window jam 12 against which it is supposed to be normally seated. The adjuster includes two sheet metal arms 13 and 14, the adjacent ends of which are provided with aligned holes to receive a pivotal pin 15 upon which the two

95

100

said arms are adapted to swing. A frictional washer 16 is also mounted upon this pin and positioned between the two connected end portions of the said arms 13 and 14. A second 5 rubber washer 17 is mounted upon the upper end portion of the pin and is covered by a metal cap 18 which in practise is firmly pressed down upon the flange of the rubber 17 after which a cotter pin 19 is positioned in 10 the hole of the pivotal pin 15 in a way to secure the parts together and form a hinged frictional joint. The arm 13 is provided with an orifice 20 in its inner end portion to receive the curled-over end portion 21 of the 15 clampable hinged member 22 whereby an eye is formed by the loop 21 to permit the inner pivotal end portion of the arm 13 to swing vertically. The member 22 is adapted to be secured in various horizontally adjusted positions by a clamping screw 23 that is threadably attached to a stud 24 formed upon a holding plate 25 that is adapted to be secured to the top of a window sill, as by means of wood screws 26. This construction permits the arm 20 13 and the connected member 22 to swing together horizontally on their respective pivots 15 and 23, and further allows the member 13 to swing vertically within the eye 21.

The outer end portion of arm 14 also includes an orifice, forming a pintle 27 that is hingedly inclosed in an eye 28 of the swivel member 29, which latter is pivotally connected to a projected arm of a bracket 30 secured to the inner face of the window sash. This 30 structure forms an operative condition substantially like that connecting the inner end of the device of the window sill, in that it provides for both vertical and horizontal movement of the arms of the adjuster, better to allow it to operate in both a horizontal and vertical plane. For the adjusting operation, it is only necessary to move the sash in or out of the position desired, against the friction of the hinged joint 16 which will hold 35 the sash in such adjusted position.

Having thus described my invention, what I claim and desire to secure by Letters Patent is:

A window adjuster comprising a fixed stud 50 for attachment to a window frame, a hinge member having a hole in one end to receive the stud for adjustment thereon, a screw on the stud to secure said member in adjusted positions, said hinge member having an eye disposed at a right angle to the stud in its other end portion, a fixed bracket for attachment to a sash, a second hinge member having one end hingedly connected to the bracket for horizontal movement and having an eye disposed at a right angle in its other end, and a pair of arms having ends hingedly connected together to swing in the same plane and the plane of the two said hinge members and having their other ends hingedly connected to

the eyes of the said hinge members so as to also swing at a right angle thereto.

Signed at Waterbury, in the county of New Haven and State of Connecticut, this 13th day of June, A. D. 1929.

FREDERICK A. CALKINS.
